UNITED STATES PATENT OFFICE

ALBERT H. SCHUMACHER, OF PASSAIC, NEW JERSEY

ROTARY CLOTH PRESS

Application filed October 7, 1929. Serial No. 397,958.

This invention relates to rotary cloth presses and has, more particularly, reference to a new and improved device for winding the cloth emerging from such press.

According to the invention, there is arranged at the delivery end of the press a winding roll which is rotatably and removably mounted in bearings carried by the press frame and which is driven through a shaft, which is adapted to be positively coupled and uncoupled with a roll and which has rotation imparted to it through a sprocket or the like gear from the press cylinder, a friction clutch being interposed between the sprocket drive and the shaft allowing a variable relative slipping motion to take place between the drive and the shaft for the purpose of preventing the winding roll from exerting an injurious stress on or changing the speed of travel of the cloth through the press when the effective diameter of the winding roll increases by the cloth winding thereon. This friction clutch permits the winding roll to retain its predetermined peripheral speed irrespective of its varying diameter, so that the cloth while being always kept sufficiently taut is not liable to be damaged by undue tension.

The winding roll preferably consists of a perforated hollow steaming roll, so that the cloth wound thereon is ready for being immediately steamed without requiring any further intermediate manipulation.

An embodiment of the subject-matter of the invention is illustrated, by way of example, in the accompanying drawings in which Fig. 1 is a transverse section of the cloth press with a winder according to the invention and Fig. 2 is a rear elevation of the same, some parts being in section and some omitted.

Referring to the drawings in detail, A is the cloth press proper and B is the winding device. The press, of which only some parts are shown, is of a conventional type comprising the frame 3, the rotary cylinder 4, the press member or bed plate 5, guide rollers 6, 6' for the cloth and the folder 7. The cylinder 4 is driven through a suitable gear-

ing of which only the main spur wheel 8 carried by the cylinder is shown.

Attached to the frame 3 are brackets 9 forming bearings 10 for the reception of a winding roll 11. This roll preferably is a hollow perforated steaming roll, as shown in Fig. 2. The bearings 10 are of such a construction as to allow a ready insertion and removal of the roll 11. In the embodiment illustrated, the bearings are open at the top and provided with lids 12 hinged at 13 and having handles 14, by which the lids may be easily swung to open position for allowing the roll 11 to be placed with its journals 15 into or lifted out of the bearings. The brackets 9 also support another guide roller 16 over which the cloth runs in its passage from the press A to the winding device B.

One of the brackets 9 has fastened to it a laterally extending arm 17, Fig. 2, forming bearings 18 for a shaft 19 which is arranged in axial alignment with the roll 11. The shaft 19 is both rotatable and shiftable in the bearings 18. At the end near the roll 11, the shaft 19 has a socket 20 of square section adapted to be engaged with an extension 21 of the same section of the adjacent journal 15 of the roll 11. The axial shifting of the shaft 19 is effected by means of a hand lever 22 which is pivoted at 23 on the arm 17. This lever has a pin 24 by which it engages a collar 25 fastened on the free end of the shaft 19.

By swinging the lever 22 to the right, the shaft 19 is coupled with and by swinging it to the left it is uncoupled from the roll 11. Loosely mounted on the shaft 19 is a sprocket wheel 26 which is driven at a constant speed through a chain 27 from a sprocket wheel 28 which is fast on the shaft of the cylinder 4. The sprocket wheel 26 is coupled with the shaft through a friction clutch consisting of disks 29, which are fastened on the hub of the wheel 26, and disks 30 splined on the shaft 19 so as to rotate with the same but allow the shaft to be axially shifted with relation to them. The sets of friction disks 29 and 30 are pressed into contact by a spring 31. The pressure exerted by this spring is adapted to be regulated by means of a tensioning device 32.

In operation, when the roll 11 has been placed in the bearings 10 and coupled with the shaft 19 through the journal extension 21 and the socket 20, the press is started and the cloth emerging from the press passes over the guide rollers 6' and 16 to the winding roll 11 to be wound thereon. The cylinder 4 through the sprocket wheel 28 and chain 27 imparts rotation at a desired constant speed to the sprocket wheel 26. This wheel transmits its rotation through the friction clutch 29, 30 to the shaft 19 and consequently to the roll 11. When the cloth is winding on the roll 11 it gradually increases the effective diameter of the same. Now, the friction clutch 29, 30 prevents this increasing diameter of the roll 11 from causing undue stress on the cloth or influencing the speed of travel of the cloth through the press. The degree of frictional contact between the disks 29, 30 is adjusted so as to cause sufficient power to be transmitted to the roll 11 to ensure winding the cloth thereon in a smooth and taut condition, but at the same time allow a variable relative slipping between the wheel 26 and the shaft 19 in accordance with the increasing effective diameter of the winding roll 11, whereby injurious tensioning of the cloth and other damages are avoided. When the web of cloth in treatment has been fully wound on the roll 11 it is removed from the press, and another one may be placed in the press in its stead. When the roll 11 is a steaming roll as shown, it may be carried immediately to the steaming apparatus for undergoing the respective treatment.

If it is desired not to wind but to fold the cloth delivered from the press it is led to the folding device 7 instead of to the winding device B.

Having thus described my invention, what I claim as new and desire to secure by Letters-Patent, is:—

1. The combination with a rotary cloth press, of a cloth winding device comprising a winding roll consisting of a perforated steaming roll, bearings for rotatably and removably supporting this roll, a shaft for driving the roll, means for coupling this shaft with the roll, a driving wheel loosely mounted on the said shaft, friction disks carried by this wheel, friction disks carried by the said shaft, and adjustable means for pressing the disks of the shaft with a predetermined pressure into frictional engagement with the disks of the driving wheel.

2. The combination with a rotary cloth press, of a cloth winding device comprising a winding roll in the form of a steaming roll, bearings for rotatably and removably supporting this roll by its journals, an extension of polygonal section on one of the roll journals, a shaft arranged in axial alignment with the roll, means for axially shifting the shaft, a socket of polygonal section on one

end of the shaft adapted to releasably receive the said polygonal extension of the roll journal for coupling the roll with the shaft, means for driving the shaft and a friction clutch interposed and allowing relative slipping motion between the driving means and the shaft, as and for the purpose described.

3. In a rotary cloth press in combination, a cylinder, a pressing member, means for guiding the cloth through the press, a winding roll for the cloth emerging from the press, bearings for rotatably and removably supporting this roll, a driving shaft for this roll arranged in axial alignment with the roll, means for coupling and uncoupling the shaft with the roll, a sprocket wheel loosely mounted on the shaft, a sprocket wheel fastened on the cylinder, a sprocket chain connecting the two sprocket wheels, and a friction clutch between the loose sprocket wheel and the shaft adapted to yieldably couple this wheel with the shaft and allow relative slipping motion between the two, as and for the purpose described.

In testimony whereof I have signed my name to this specification.

ALBERT H. SCHUMACHER.
